UNITED STATES PATENT OFFICE.

CHARLES A. FETTERS, OF WASHINGTON, DISTRICT OF COLUMBIA.

COAT-HANGER ATTACHMENT.

Application filed August 3, 1923. Serial No. 655,434.

To all whom it may concern:

Be it known that CHARLES A. FETTERS, a citizen of the United States, residing at Washington, in the District of Columbia, has invented certain new and useful Improvements in Coat-Hanger Attachments, of which the following is a specification, reference being had therein to the accompanying drawings.

10 The invention relates to coat hanger attachments and has for its object to provide a supporting hook, which may be easily and quickly attached to the shank of a supporting hook of a coat hanger whereby additional articles, for instance hats, underskirts and the like may be supported on the coat hanger, at the same time the coat is supported thereon.

20 A further object is to form the hook from a single piece of wire bent to form spaced eyes adapted to engage the shank of the hook of the coat hanger, which eyes are carried by the spring arms, which may be forced together for positioning the eyes adjacent each other, thereby allowing the device to be easily and quickly passed over the coat hanger hook and onto the shank thereof. The eyes bind on the shank of the hook when a weight is suspended therefrom, and the hook may be positioned in the same plane as the supporting hook of the hanger, thereby allowing the hangers to be shipped in a compact package without interference from the additional hook.

30 With the above and other objects in view the invention resides in the combination and arrangement of parts as hereinafter set forth, shown in the drawing, described and claimed, it being understood that changes 40 in the precise embodiment of the invention may be made within the scope of what is claimed without departing from the spirit of the invention.

45 In the drawing:—

Figure 1 is a perspective view of a conventional form of coat hanger, showing the garment hook attached thereto.

Figure 2 is a side elevation of a coat hanger showing the garment hook applied to the shank thereof.

Figure 3 is a horizontal sectional view taken on line 3—3 of Figure 2.

Referring to the drawing, the numeral 1 designates the body of the coat hanger, and 2 a supporting hook carried thereby, which hook is attached to the body 1 by

means of the shank hook 3. It has been found that it is often necessary to hang other garments on a coat hanger, for instance, a hat, an underskirt or a wrap, which has been impossible, especially in the case of a hat. To obviate this disadvantage the garment hook 4 is provided, which hook is formed from a single piece of wire bent upon itself at 5 to form a hat receiving hook 6, which is relatively stiff, incident to the parallel portions 7, which engage each other. One of the parallel portions 7 terminates in a horizontally disposed portion 8 bent upon itself to form an eye 9 for the reception of the shank 3 and a parallel portion 10, the outer end of which terminates in downwardly extending hooks 11, on which a garment may be hung, such for instance as a skirt. The arms 8 and 10 are slightly spaced apart thereby allowing a gripping action by the eye 9 on the shank 3, thereby preventing easy displacement of the garment hook, when in position on the shank 3. One of the arms 7 is provided with an upwardly and inwardly extending spring arm 12, which arm terminates in an eye 13 in which the shank 3 is disposed at a point spaced from the eye 9, consequently the garment hook 4 is rigidly supported when garments are supported thereon. Under the weight of the garments the eye 13 binds on the shank 3 and rigidly braces the garment hook. When the device is being placed on the hook 2 and shank 3, the arms 12 and 8 are sprung towards each other, thereby positioning the eyes 9 and 13 close together and consequently the hook 2 and shank 3 may be easily passed through the eye, even around bends as shown at 14 at the upper end of the shank, therefore the device may be easily applied to coat hanger hook shanks of various shapes. When it is desired to store the hangers, for instance for purposes of shipment, or when not in use, the hook may be moved upwardly on the shank 3 to a position where it can be moved into the same plane as the body 1 of the coat hanger, therefore it will be seen that it will not take up any additional room and at the same time allow the hangers to be easily stacked or formed into compact packages and the frictional engagement of the eye 9 and the eye 13 on the shank 3 will maintain the garment hook in any position to which it may be moved.

From the above it will be seen that a gar-

ment hook is provided, for coat hangers, which may easily and quickly be applied to the shank of the supporting hook of the coat hanger and moved to a position for 5 use at a right angle to the body of the coat hanger or to a position in the same plane as the coat hanger for purposes of storage and shipment.

The invention having been set forth what 10 is claimed as new and useful is:—

The combination with a coat hanger hook, a vertically disposed shank carried by said hook, of a garment hook carried by said shank, said garment hook being formed

from a single piece of spring wire bent up- 15 on itself to form an upwardly extending hook and inwardly diverging arms, parallel horizontally disposed eyes carried by said diverging horizontal arms and in which the shank is disposed and frictionally held, the 20 lower eye terminating in an outwardly extending arm, and a hook carried by the outwardly extending arm below the first mentioned garment supporting hook.

In testimony whereof I hereunto affix my 25 signature.

CHARLES A. FETTERS.
